DESIGN FOR A BICYCLE MUD GUARD OR SIMILAR ARTICLE

Ewald F. Pawsat, Maysville, Ky., assignor to Wald
Mfg. Co., Inc., Maysville, Ky., a corporation of
Kentucky

Application January 25, 1937, Serial No. 67,265

Term of patent 14 years

To all whom it may concern:

Be it known that I, Ewald F. Pawsat, a citizen
of the United States of America and a resident
of Maysville, in the county of Mason and State
of Kentucky, have invented a new, original, and
ornamental Design for a Bicycle Mud Guard or
Similar Article, of which the following is a speci-
fication, reference being made to the accompan-
ying drawing, forming a part thereof.

Fig. 1 is a transverse sectional view of a bi-

cycle mud guard or similar article, on line 1—1
of Fig. 3, and on an enlarged scale.

Fig. 2 is a perspective view of a bicycle mud
guard or similar article showing my new design.

Fig. 3 is a rear elevation of the design shown
in Fig. 2.

I claim:

The ornamental design for a bicycle mud guard
or similar article, as shown.

EWALD F. PAWSAT.
